DESIGN FOR AN AIR CONDITIONING CABINET

Arthur W. Conley, Shaker Heights, Ohio

Application March 16, 1936, Serial No. 61,647

Term of patent 7 years

To all whom it may concern:

Be it known that I, Arthur W. Conley, a citizen of the United States, residing at Shaker Heights, in the county of Cuyahoga and State of Ohio, have invented a new, original, and ornamental Design for an Air Conditioning Cabinet, of which the following is a specification, reference being had to the accompanying drawing, forming part thereof, wherein Fig. 1 is a top plan view; Fig. 2 is a front elevation; and Fig. 3 is an end elevation of an air conditioning cabinet showing my new design.

I claim:

The ornamental design for an air conditioning cabinet substantially as shown.

ARTHUR W. CONLEY.
